UNITED STATES PATENT OFFICE.

MARVIN H. JESTER, OF DENVER, COLORADO, ASSIGNOR TO THE M. H. JESTER INVESTMENT COMPANY, A CORPORATION OF COLORADO.

METALLIC STUDDING AND METAL YOKING-CLIP FOR SUPPORTING AND SECURING PLASTER-BOARDS TOGETHER IN PARTITION CONSTRUCTION.

1,087,019.

Specification of Letters Patent. Patented Feb. 10, 1914.

Application filed January 4, 1913. Serial No. 740,177.

To all whom it may concern:

Be it known that I, MARVIN H. JESTER, a citizen of the United States of America, residing in the city and county of Denver and 5 State of Colorado, have invented a new and useful Metallic Studding and Metal Yoking-Clip for Supporting and Securing Plaster-Boards Together in Partition Construction, of which the following is a specification.

10 My invention relates to improvements in metallic studding and metal yoking clips for supporting and securing plaster boards together in partition walls, into skeleton partitions adapted to receive plastering materials in constructing plastered partition 15 walls in buildings.

The object of the invention is to provide a cheap and simple clip for securing plaster boards to metal channel bar studs, so that 20 the said boards may be arranged with either the straight or staggered form of joint. Further, to provide a clip which is frictionally held upon the stud, thus enabling any number of clips to be secured in position on the studding before the plaster boards are attached, thereby greatly reducing the time and labor otherwise required in such work. I attain these objects by the 25 mechanism illustrated in the accompanying drawings, in which:

Figure 1, is a front view illustrating a plurality of plaster boards secured to studding so as to form straight or unbroken joints. Fig. 2, is a similar view showing the staggered joint arrangement. Fig. 3, is a horizontal sectional view illustrating the application of the form of clip used when the plaster boards are connected to the studding in staggered form. Fig. 4, is a perspective view of the form of clip shown in Fig. 3. Fig. 5, is an edge view of the same, showing a portion of a stud to which the clip is secured, and a portion of a plaster board clamped to the clip. Fig. 6, is a horizontal sectional view showing the application of the form of clip employed, when the boards are arranged with straight joints. Fig. 7, is a perspective view of the clip shown in Fig. 6. Fig. 8, is a perspective view showing a form of clip used in joining a portion at right angles to another partition. Fig. 9, is a horizontal sectional view illustrating the application of the clip shown in Fig. 8. And Fig. 10, is a horizontal sec-

tional view showing a clip employed in making a joint in the partition around a vertical pipe.

Similar letters of reference refer to similar parts throughout the several views.

Referring to the drawings,—the numeral 60 1 designates a metal stud, preferably a channel bar stud, as I preferably use the channel bar form of stud in preference to other forms of metal stud, such as flat metal-bars, T bars, Z bars, or V bars.

65 2 designates a metal yoke-shaped clip, which is formed to fit over the channel bar and extend beyond it a short distance, and over its free ends I place a plate 3, which is provided with an aperture 4, in its center, 70 that is made to permit the yoke clip to extend through it and fit snugly in it. This aperture is formed by cutting slots through the plate in such a way as to release two equal sized tongue portions 5, which are 75 bent downwardly and backwardly so as to lie alongside of and to fit snugly and preferably firmly enough against the opposite sides of the yoke clip to require pressure of the thumb of a partition erector to force 80 the yoke-shaped clip through the aperture and between and through the aperture in the plates, thus making a self-sustaining, combining and holding fit between the yoke clip, the channel bar, and the plate, which 85 permits them to stay assembled together wherever placed along the vertical height of the channel bars without slipping apart from each other, which is a feature of importance when erecting partitions, as it 90 enables one man to erect partitions without any assistance, as would be the case if these parts were so loosely fitted together as to slip easily apart, in which case they would have to be held by one man while another 95 placed the plaster boards 7 in position to be securely keyed or locked to them.

100 The plaster boards 7 are thin boards made of plaster of Paris, and other materials, and are extensively manufactured and used in buildings as a background or support for stucco and other plastering materials. These boards are made in various sizes as to width, length and thickness, those of about a quarter inch to five-sixteenths of an inch by two feet square, or two feet by three feet long, or eighteen inches wide by two feet or thirty inches

long, being most generally used for partition work. I preferably use plaster boards of five-sixteenths inch thickness by two feet wide and three feet in length, with the channel bar yoke clip construction illustrated.

The clips 2 are about twice the length of the width of the channel bars' studs 1, so that when they are placed upon the channel bars their free ends extend beyond the said bars a distance greater than the thickness of a plaster board, and these ends are provided with holes 8, which are so positioned that their centers are distant from the plates 3 a space corresponding to the thickness of a plaster board. When the boards are placed against the plates 3, with their ends abutting against the sides of the clip 2, as shown by Fig. 3, the ends of the boards will partially conceal the holes 8, and the boards are clamped to the plates by passing a suitable wedge, such as a wire nail 9, through the holes 8, and as the space between the outer margin of the holes and the surface of the plaster boards is less than the diameter of the nails, the insertion of the nail causes the ends of the boards to be securely clamped to the plates 3.

The form of clip illustrated in Figs. 3, 4, and 5, is employed when the plaster boards are arranged in staggered form as shown by Fig. 2. In this arrangement the studs do not lie between the adjoining ends of the boards, but are back of the plates 3, against which the boards rest, so that they permit the boards to be secured with the adjoining ends of each alternate row in the same vertical line, or so as to form staggered joints. By thus eliminating an unbroken joint throughout the length of the studs, the tendency of the cracking of the plaster at these points is greatly lessened.

When boards are used of a length corresponding to the space between three studs, the boards are secured to the intermediate stud by forming holes 2^a in them centrally of their length, through which the ends of clips 2 on the intermediate stud may pass, and nails 9 are passed through the ends of the clip, as in the manner above described for clamping the boards at their centers. I have illustrated one clip at the center of each board, but I may employ two clips, placing them in line with the clips at the ends of the board.

In Figs. 6 and 7 is illustrated the form of clip employed in securing the plaster boards with straight or unbroken joints, which arrangement is shown in Fig. 1. In this arrangement I employ the yoke-shaped clip 2, but in connection with a different form of plate. The plate 10, which is used in this connection, is bent to form a central vertical U-shaped channel 11, the sides of which terminate in right angled wings 12. The depth of the channel 11, is about one-half of

the width of a channel bar stud, or slightly less than the thickness of a plaster board, as shown by Fig. 6. Vertical parallel slots 13 are cut in the end wall of the channel 11, to permit the insertion of the ends of the clip 2, and the strip 14, released by the cutting of these slots, is outwardly bowed, as clearly shown by Fig. 7. In practice, the clips 2 are sprung upon the studs, and the plates 10 are placed on the studs, and over the projecting ends of the clips, so that the said projecting ends extend through the slots 13, in the channel of the plate, on each side of the bowed strip 14. By forming the plate 10, with a channel which fits over the stud, the wings 12 of said plate are positioned on a line with the center of the width of the stud, instead of in line with the front side of said stud, as in the plate shown in Fig. 3, and as only half the width of the stud extends beyond the back of the plate, a coat of plaster of less thickness can be used in this arrangement, than in that shown in Fig. 3, and consequently a thinner partition constructed. The plaster boards are placed against the wings 12, with their ends abutting against the studs, which in this arrangement lie between the said ends, and the boards are secured or clamped to the plates by passing wire nails through the holes in the ends of the clips and beneath the bowed strips 14, as clearly shown in Fig. 6, thus securing the boards so that their ends form straight or unbroken joints.

In Fig. 8, is illustrated a perspective view of a clip 15, which is employed in connecting the ends of plaster boards of one partition to those of another partition extending at right angles to the first partition, and this clip may be employed at adjoining corners, or at any point between two corners as shown by Fig. 9. These clips comprise substantially S-shaped portions, the folds 16 of which are adapted to engage the ends of plaster boards of a partition 17, while the opposite folds 18 are adapted to fit over one of the studs of a partition 19 at right angles to the partition 17, and the folds 18 terminate in right angled wings 20, which bear upon the ends of the plaster boards of the partition 19, and form a bracing medium. With clips of this character, a partition can be conveniently and effectively joined to another partition extending at right angles thereto, as will be fully understood by reference to Fig. 9.

In Fig. 10, is shown a clip 21, by means of which an off-set can be formed in a partition where a vertical pipe occurs. The clips 21 are S-shaped and their folds 22 are adapted to receive the ends of plaster boards 23, which come in line with a pipe 24, which may be either a steam, water, or gas pipe, and the folds 25 of these clips receive short boards 26, which form a connecting medium

for the opposing ends of the boards 23, as shown, by which an intervening space is provided to receive the said pipe 24. When the plastering is applied, the pipe and board 5 26 are concealed.

Having described my invention, what I claim as new and desire to secure by Letters Patent, is:

1. In a securing device for plaster boards 10 as specified, the combination with studding, of U-shaped clips thereon of greater length than the width of the studs, and provided with holes in their free ends, plates on said studs having central apertures through 15 which the ends of the clips extend, and nails extending through the holes in the ends of said clips thereby to clamp the ends of plaster boards to said plates.
2. In a securing device for plaster boards 20 as specified, the combination with studs, of U-shaped clips in clamping engagement with the studs, the free ends of which extend beyond the studs and are apertured, centrally apertured plates on the extended 25 ends of the clips in clamping engagement therewith, and bearing upon the studs, and nails passed through the apertured ends of the clips thereby to clamp the ends of plaster boards against the plates.
3. In a securing device for plaster boards 30 as specified, the combination with a stud, of a clip straddling said stud, an apertured plate fitting over said clip, and a nail passed through the clip at a distance from 35 said plate for clamping the ends of plaster boards to said plate.
4. In a securing device for plaster boards 40 as specified, the combination with a stud, of an apertured channeled plate engaging one 45 side of the stud, a U-shaped clip on the opposite side of the stud, the ends of which extend through the aperture of and beyond the channel of said plate and are apertured, and a nail which is passed through the said apertures thereby to clamp the ends of plaster boards to the plate.
5. In a securing device for plaster boards 50 as specified, the combination with a stud, of an apertured plate thereon having a channel portion which receives the stud, a U-shaped clip on the opposite side of said stud, having apertured ends which extend

through the aperture of said plate and beyond said channel, a nail receiving member on the channel, and a nail which is 55 passed beneath said member, and through the apertures in the clip, thereby to clamp plaster boards to the plate.

6. In a securing device for plaster boards as specified, the combination with a stud, of 60 a plate having a longitudinal channel which fits over said stud and having parallel slots therein, a U-shaped clip on said stud having apertured ends which extend through said 65 slots, and a clamping element which passes through said apertured ends.

7. In a securing device for plaster boards as specified, the combination with a stud, of 70 a plate having a channel portion in engagement with the stud and having parallel slots, and a strip formed by said slots, which is outwardly bowed, a U-shaped clip on the stud having apertured ends which extend through said slots, and a nail which is passed 75 through the apertured ends beneath said outwardly-bowed strip.

8. In a securing device for plaster boards, the combination with a stud, of clip-plates 80 having means engaging said stud and having extended portions of greater length than the width of the stud and provided with apertures in the ends remote from said stud, plates on said studs having apertures through which said remote ends of the clips 85 extend, and keys in the apertures of the ends of said clips for securing the plaster boards against said plates.

9. In a securing device for plaster boards, the combination with a stud, of clip-plates 90 having means engaging said stud and having extended portions of greater length than the width of the stud, plates on said stud having apertures through which pass the ends of said clips remote from said stud, and means at said remote ends of the clips 95 for securing the plaster boards against said plates.

In testimony whereof I affix my signature in presence of two witnesses.

MARVIN H. JESTER.
